EMBANKMENT FOR ROADS, RAILROADS, AND THE LIKE

Filed March 9, 1927

Inventor:

Lars Harald Pöpke

UNITED STATES PATENT OFFICE

LARS HARALD PÖPKÉ, OF SOLLEFTEA, SWEDEN

EMBANKMENT FOR ROADS, RAILROADS, AND THE LIKE

Application filed March 9, 1927, Serial No. 174,040, and in Sweden March 9, 1926.

This invention relates to embankments for roads, railroads and the like in cold countries. The object of the invention is to counteract and as far as possible prevent the well-known rising or swelling of the embankments when the frost breaks up in spring-time.

According to general opinion the frost in the ground is formed in the following way: At the first stage of the frost formation the water present in the moist soil freezes to ice at the surface. Thereupon ground water penetrates upwards on account of the capillary force and is deposited as ice on the underside of the already formed crust. It has also been believed that water in the form of vapour is conveyed through the cavities in the ground from the deeper moist layers and is condensed below the frozen crust due to the well-known physical "law of the cold wall". The water thus condensed is thereupon frozen to ice by the chill from the outside. The frost crust is gradually growing in the last named way causing the layers above the frost-proof depth finally to contain considerably more water than the same would have been able to absorb in an unfrozen state. This causes the frost to break up and the soil becomes soft, even practically liquid, and therefore will be less or not at all able to withstand the pressure exerted by vehicles, horses, etc. In the frozen ground in winter-time also rising or swelling occurs due to the frost which is especially troublesome in railroad banks. Above named disadvantages are particularly great when certain kinds of clay are present in the ground.

As above described three different factors contribute to the frost formation, namely:

- 40 1. Surface water or free water;
2. Capillary water; and
3. Condensed water.

It has been tried to reduce the mentioned disadvantages by laying twig or sand beddings below the road or railroad embankment, thereby trying to prevent the frost from penetrating into the same. Experience has, however, proved that such a method not at all or only in a very little degree will eliminate the said disadvantages.

According to this invention the disadvantages of the frost are eliminated by trying to prevent the admittance of water to the road embankment or the like during the cold season, thus preventing frost formation in the 55 same as far as possible.

According to the invention this is achieved when building or rebuilding roads, railroads, foundations, etc., by laying in the embankment or the like at suitable depth one or more 60 layers of a tight material that does not transmit water or water vapour. By this method condensed water and capillary water are entirely prevented from penetrating into the embankment and form frost. The said layer 65 should be in the main parallel with the above surface of the embankment so as to evenly distribute the pressure to the ground below.

The layers may preferably be made out of sheet iron, plane or corrugated, or out of 70 wood or other material that does not transmit water or water vapour.

The invention is illustrated by way of example in the accompanying drawing, wherein is shown a cross-section through a road embankment provided with one layer of a tight material.

The tightening layer 1 may be made out of sheet-iron, suitably galvanized or in other way made rust-proof. It may also be made 80 out of other suitable tight material.

In order to prevent sliding of the part of the embankment above the plate 1, the latter may be provided with angle irons 2, projections or the like in the length direction of the 85 road.

The plate shown in the figure is plane but may also be corrugated.

When embedding a layer of tight material in the embankment in accordance with the 90 invention, the road body above the same will become safe against the admittance of condensed water and capillary water. The cavities in the ground above the tight layer will therefore contain an ordinary quantity of 95 air. But as air in comparison with ice is a very bad heat conductor, the road body both above and below the tight layer will be much better insulated against the chill. The chill will be much less able to penetrate down 100.

through the embankment so that a considerable decrease in the frost-proof depth is reached. In fact the ground below the tight layer will also be frost-proof so that the said layer will be embedded practically entirely in frost-proof soil.

5 I claim:—

A road, railroad and the like embankment consisting of an earth fill comprising a sheet 10 material and water impervious layer in said fill arranged substantially horizontal under the road; and a substantial layer of earth between the road and the sheet layer, said sheet layer being adapted to prevent the 15 ground moisture from creeping upwardly and depositing in the earth layer under the road.

In testimony whereof I have hereunto set my hand.
